MURPHY D. SMITH, WALTER MORGAN, AND WILLIAM DAVIS MOORE, OF BIRMINGHAM, ALABAMA, ASSIGNEES TO SAND SPUN PATENTS CORPORATION, OF NEW YORK, N. Y., A CORPORATION OF DELAWARE.

AUTOMATIC CONTROL FOR CENTRIFUGAL-CASTING MACHINES.

Application filed July 28, 1926. Serial No. 125,356.

This invention is an improvement in centrifugal casting methods and machines, and more particularly in mechanism for automatic control of the motor which rotates the mold through the movement of the mold.

In casting centrifugally in refractory or sand lined molds, by the method set forth in Patents Nos. 1,620,829, 1,620,830, 1,620,831, of March 15, 1927, the molten metal is charged into a tilted or inclined mold, while the mold is rotating at a speed insufficient to hold the metal on the mold wall by centrifugal force. The longitudinal distribution of the molten metal is attained by the movement of the mold to level position, and this leveling operation may be completed at or near the completion of charging, and during the rotation at a relatively low speed. That is the operations of charging and leveling are co-incident and substantially co-extensive.

After the completion of the longitudinal distribution of the molten metal, or the substantial completion, the speed of rotation of the mold is increased to a relatively high rate, sufficient to apply the metal to the mold wall and to hold it thereon by centrifugal force, thus attaining circumferential distribution of the metal.

In Patent No. 1,620,829, mechanism is shown and described controlled by the movement of the mold toward level position to increase the speed of the motor. However, the moment at which high speed should be initiated varies in accordance with many factors, and it is desirable to be able to select the moment to initiate the change from low to high speed, and to vary the time required for attaining the high from the low speed.

It is also desirable that in the control of the relative speeds of the motor the human element be eliminated as far as possible, that is that the process from start to finish be as nearly automatic as is possible, and while capable of regulation, of a nature such that when once regulated the process will repeat indefinitely, every repetition a replica of the preceding.

One of the primary objects of the present invention is the provision of mechanism for automatically controlling the motor to rotate

the mold at selected and different speeds during the course of the casting operation wherein the mechanism once set into operation will inaugurate and complete a sequence of operations.

Another object is the provision of charging means for the mold operated by the movement of the mold toward level position, and co-ordinated with the operation of the controlling mechanism, so that the charging will be co-incident and substantially co-extensive with the leveling movement and related in a selected manner to the changes in motor speed.

Another object is the provision in a tilting mold normally biased by gravity to level position, hydraulic elevating mechanism for tilting the mold, and motor speed changing means controlled by the exhaust of the hydraulic mechanism to first increase and afterwards reduce the motor speed.

Another object is the provision in such motor changing means of mechanism enabling the moment of initiating the increased speed and the duration of the change from low to high to be varied.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims may be resorted to without departing from the spirit of the invention.

In the drawings forming a part hereof:

Fig. 1 is a diagrammatic side view of a casting machine provided with the improved motor speed changing mechanism.

Fig. 2 is an end view of the mechanical control.

Fig. 3 is a plan view of Fig. 2.

Fig. 4 is a side elevation of Figure 3.

Fig. 5 is a side elevation of an alternate arrangement of speed controlling mechanism.

The present embodiment of the invention is shown in connection with a casting machine of the character shown in Patent No.

1,620,831, granted to W. D. Moore, on March 15, 1927, wherein the machine includes a tilting carriage 1, pivoted at 2, near one end, to swing into inclined or substantially horizontal position. The mold is rotatably supported on the carriage beneath the hood 3, and it is rotated by means of an electrically controlled motor 4, mounted to slide on the carriage toward and from the mold, and 10 coupled to and released from the mold by such movement, the coupling mechanism being indicated generally at 5.

The motor is controlled by a controller indicated generally at 6, arranged at the end 15 of the carriage, and the controller shaft 7 has the usual hand operated mechanism 8 therefor.

The carriage is tilted or inclined by means of plungers 9 moving in hydraulic cylinders 20 10, the plungers having friction rollers 11 upon which the carriage loosely rests. When fluid under pressure as for instance water, is admitted to the cylinders by the pipe line 11', the plungers are lifted, and the 25 carriage is inclined. The carriage moves to horizontal position by its own weight, when the cylinders are open to permit the water to discharge.

The molten metal is charged into the mold 30 from a tilting ladle 12 mounted on a ladle support 13 hinged at the end of the hood remote from the motor, and the metal is conducted from the ladle to the mold by a pouring spout, all as shown and described in the 35 above mentioned application. The ladle is tilted by a lever 14 pivoted at 15 intermediate its ends, and having one end in position to be engaged and moved downward by the carriage as it moves to level position. Between 40 the other end and the ladle is arranged an adjustable strut, detachably connected at its upper end with an arm 17 on the ladle, and at its lower end to the lever by a cam plate 18, the construction and operation of which is fully described in the above 45 mentioned application.

The flow of the fluid under pressure to the cylinders through the pipe line 11' is controlled by a three-way valve indicated generally at 19. This valve is interposed in the pipe between the source of supply 20 and a pressure tank 21. The pressure tank is provided with a gauge 22, and a throttle valve 23 is arranged between the tank and the 50 valve 19. A by-pass 24 is arranged around the three-way or controlling valve 19, the bypass having the usual valve 24' for varying the capacity thereof, and a handle 19' is provided for operating the valve 19.

A pipe 25 leads from the pressure tank to a float tank or chamber 26, and this pipe is provided with a calibrating orifice 27, which is adjustable to vary the discharge capacity of the pipe. The float tank has an overflow 55 28, and a bleed or drain pipe 29 controlled

by a valve 30, both pipes discharging into a common drain 31. A float 32 is arranged in the float tank, and a rod or stem 33 is connected with the float, the stem having guided movement at its top and bottom as shown. 70 When the three-way valve 19 is opened to admit fluid under pressure to the cylinders 10, a part of the fluid passes through the bypass 24 to the pressure tank 21, and from the tank by way of the pipe 25 to the float 75 chamber 26. The flow of liquid is greater than can discharge through the drain pipe 29, and the level of the liquid in the chamber rises, raising the float, which through the rod or stem 33 operates switches controlling 80 the motor circuits.

In practice, during the charging of the mold it is rotated slowly, at a speed of about 50 R. P. M. At or near the moment when the mold reaches the horizontal, the speed 85 is rapidly increased to about 1250 R. P. M. After a relatively short time, long enough for the metal to set, the speed is decreased to about 900 R. P. M. The mold continues to rotate at this intermediate speed until the 90 metal has sufficiently set, after which the motor circuit is opened, and the mold ceases to rotate.

Automatic mechanism is provided for moving the controller shaft in a direction to speed up the motor at a selected moment. This mechanism is set into motion by the mold at or about the time when it attains the horizontal position, and once set in motion, the mechanism continues to operate 100 of itself. The said mechanism includes a cylinder 34 secured to the controller shaft, transversely thereof, by means of a T bracket 35. The ends of the cylinder are closed, and a ball 36, as for instance a cannon ball of suitable size is arranged in the cylinder. The ends of the cylinder have buffers 37 for cushioning the movement of the ball, from end to end of the cylinder. With the controller shaft in neutral position, the cylinder 105 will occupy the position of Fig. 2, that end of the cylinder which would be moved upward were the controller shaft handle advanced being slightly lower than the other end.

Beneath this end of the cylinder is arranged an extension 38 of an arm 39 extending longitudinally from the tilting frame. A set screw 40 is threaded through the end 110 of the extension, in position to engage the cylinder when the arm is moved upward, thereby to tilt the same. This set screw has the usual lock nuts as shown and the extension is pivotally connected with the body of the arm, the pivotal connection being indicated at 41. It will be evident from the description that when the frame or carriage moves to level position the arm will tilt the cylinder, and the ball will roll to the opposite end thereof. This tilting movement of 115 120 125 130

the cylinder will operate the controller shaft to increase the speed, and the time required to pass from 50 R. P. M. to 1250 R. P. M. may be nicely regulated by the check shown in Fig. 2.

The check is of the dash pot type, such as is used for door checks, including a fixed part 42 secured to the base 43 of the controller, and a movable part 44 connected by 10 a link 45 with a radial arm 46 on the controller shaft. The check acts as a brake on the movement of the cylinder 34, and by adjusting the relation between the fixed and movable parts of the check in a usual and 15 well known manner, the extent of the braking action may be varied, thus to vary the duration of the time between the commencement and end of the cylinder's movement. As the ball begins to roll, and especially as 20 it passes the controller shaft, the cylinder quickly moves toward the vertical, and an adjustable stop 47 is provided on the controller base for engagement by the cylinder to limit its movement toward the vertical.

25 When the controller shaft is returned to neutral position, the cylinder moves to the position of Fig. 2, and in order to enable this movement while the carriage is horizontal, the pivotal connection between the 30 extension 38 and the body of the arm 39 is provided. The extension may be swung manually out of the way of the cylinder to enable the cylinder to move to the position of Fig. 2. To insure that the extension will 35 be in operative position when the carriage again moves toward level position after being tilted, a cam 48 is provided. This cam is a frame of right triangular shape, and is so arranged that as the carriage moves from 40 horizontal to inclined position the extension will engage the hypotenuse of the frame, and will be returned into alignment with the body of the arm.

45 As previously mentioned, the float valve 32 operates switches which control the motor circuits. One of these switches 49 is interposed in a branch circuit 50 from the main supply circuit 51 of the motor. The switch includes a switch arm 52 pivoted at 52^a normally urged or biased to circuit closing position by a counterweight 53 on one end of the arm. The other end bears against a stop 54 adjustably mounted on the rod 33, the arrangement being such that when the float 55 moves upward, the arm may swing under the pull of the counterweight, to close the branch circuit 50. A magnetic contactor switch 55 of usual construction has the windings of its magnets interposed in the branch circuit, 60 and the cores of the magnets operate to close the main motor circuit 51 when the coils are energized.

65 A second magnetic contactor switch 56 is arranged in a branch 57 from the main motor circuit. This switch 56 is in series

in the branch circuit 57 with a second switch including a contact element 58 supported by a rod 59 having guided movement parallel with the rod 33, and a contact element 60 on the rod. The arrangement is such that 70 when the float attains a predetermined height in its upward movement, the contact elements 58 and 60 touch and close the branch circuit 57. The rod 59 is movable vertically, so that contact between the elements 58 and 60 is maintained throughout a part of the travel of the float. When the elements 58 and 60 are in contact, the switch 56 in the same branch circuit is energized, and keeps open a branch shunt circuit around 75 a portion of the motor field resistor, and allows the motor controller to regulate the speed of the motor by virtue of the position of the controller shaft and lever. When the elements 58 and 60 are not in contact, however, the magnet coil of switch 56 is de-energized, allowing contacts to be made which close the shunt around a portion (which may be varied) of the field resistor, thereby imparting a stronger field current to the motor 80 which reduces the speed of the motor. This is done irrespective of the fact that the controller shaft and lever are set to such position as to normally impart a higher speed of 85 rotation to the motor.

90 In order that the operator may recognize the precise moment when the frame and mold attain the horizontal, a signal is provided, controlled by the movement of the frame or carriage 1. This signal, in the 95 present instance an electric light 65, is interposed in a branch circuit 66 from the main circuit. One of the terminals of the circuit is connected to a contact element 67 on the controller base, and the other with an element 68 on the carriage or frame. The arrangement is such that the moment when the carriage moves into level position, or immediately prior to the attainment of such 100 position, the contact elements 67 and 68 will engage, closing the circuit, and displaying the signal. A suitable speed indicator 69 is provided for indicating to the operator the speed of the motor, and this is arranged in 105 a convenient position for inspection, in a circuit indicated at 70.

110 The operation of the mechanism just described is as follows. When ready for casting, by means of the threeway valve 19 water is admitted to the cylinders 10. The plungers move upward, and the carriage is tilted into the position of Fig. 1. Through the bypass 24 a part of the water passes by way of the pressure tank and the pipe 25 to the float chamber 26, and the float begins 115 to rise. At a predetermined moment in the rise thereof, the contacts 58 and 60 engage, after which the contact 58 moves with the contact 60, maintaining the branch circuit 120 57 closed, and the switch 56 energized. At 125

about the time when the mold attains the inclined position of Fig. 1, the water level in the tank 26 is at the level of the overflow 28, and the float is in its highest position. As the float lifts, the switch 49 operates, and the switch 55 is energized to close the main motor circuit.

The controller handle 8 has meanwhile been set at one point, and the motor begins to rotate at a speed of about 50 R. P. M. The charge is poured into the ladle, and the valve 19 is opened to permit the cylinders 10 to exhaust through the pipe line 11'. As the carriage moves downward, the ladle is tilted, and the molten metal is discharged into the mold, the relation between the ladle and mold, and the co-ordinated movement of ladle and mold being such that a stream of substantially uniform volume is delivered into the mold throughout the time of its travel from inclined to horizontal position, the leveling and charging operations being co-incident, and substantially co-extensive.

At or about the moment when the mold reaches the horizontal, the extension 38 of the arm 39 engages the cylinder 34, which tilts the same far enough so that the ball begins to roll. The momentum of the ball increases rapidly, and the controller shaft is advanced, to speed up the motor. The movement of the controller shaft to speed up the motor is initiated by movement of the carriage to horizontal position, but it is completed in a variable length of time by the movement of the ball, the time required to complete the speeding up from 50 R. P. M. to 1250 R. P. M. being regulated by means of the check. The moment when the cylinder begins to tilt also may be varied by means of the set screw 40.

When the carriage and mold are in horizontal position, water no longer discharges into the float chamber. The drain valve 30 has been set to discharge the water through the pipe 29 at a rate such that the float will reach its lowest position in a predetermined time, as for instance three and one-half minutes. When the float has moved downward a selected distance, the contacts 58 and 60 disengage, and the switch 56 is operated to close the circuit 61, shortcircuiting a portion of the motor field resistance. The field strength is increased and the motor speed is reduced to any extent desired, as for instance 900 R. P. M. This speed continues until the water level in the tank 26 is such that the float is in extreme low position, at which time the stop 54 engages the switch arm of switch 49, and operates the same to open the motor circuit 50 stopping the motor.

It will be evident from the description that by the above arrangement, the operation of the motor is entirely automatic, and is automatically synchronized with the pouring of the metal and the lowering of the

carriage, and that the operation is controlled by a single mechanism, namely the valve 19. While the arrangement is such that the operation is completely automatic and controlled by the valve 19, yet the manual control of the motor is at all time available to the operator, and may be used in emergencies.

The automatic control is shown applied to a tilting casting machine, but it is obvious that the same principle, and substantially the same mechanism may be used in connection with a non-tilting or fixed pipe casting machine. Such arrangement is shown in Fig. 5. In this arrangement, a hydraulic cylinder 75 is provided, in which is arranged a plunger 76 having a lost motion connection at its upper end with one end of a lever 77 pivoted at 78 near the casting machine, indicated at 79. The plunger 76 is counterweighted, the weight being indicated at 80, in such manner that when the cylinder 75 is opened to exhaust, the weight will force the plunger downward in a predetermined length of time. A cylinder 81 corresponding in all respects to the cylinder 34, is secured to the controller shaft 82 in the same manner as the cylinder 34 is secured to the controller shaft 7. This cylinder has the ball 83 therein, and one end is connected by a stirrup 84 with the lever 77 intermediate its ends and on the opposite side of the pivotal connection from the plunger 76.

The pipe line 74 of the cylinder 75 is connected with the same mechanism of controlling valve, pressure tank, bypass, float mechanism, and switches as is the pipe line 11 of Fig. 1. That end of the lever remote from the plunger 76 is connected with the pouring ladle not shown, for the molten metal by the strut 77a corresponding to the strut 16 of Figure 1. The operation is substantially the same as the construction of Fig. 1. When ready for casting, the weight 80 is lifted, and descends as the ladle empties. The sequence of operation on the part of the float and switches is the same, and the same results as regards motor speeds are attained. The lever 77 is connected to the cylinder 81 by a stirrup in the manner shown, so that it may be released when returning the cylinder to horizontal position. That is the stirrup serves the same function as the pivotal connection of the Fig. 1 construction.

It will be evident from the description that the charging of the mold is synchronized with the change in speed, and that in both constructions the charging mechanism initiates the operation of the speed changing means. In the Fig. 1 construction the charging mechanism includes the tilting ladle, the tilting frame, and the connection between them whereby when the frame is leveled the ladle is tilted. In the arrange-

ment of Fig. 5, the charging mechanism is the ladle and the operating means therefor, which may be of any suitable character.

In both constructions the change in speed is related to the position of the mold and to the charging of the molten metal. In the first instance the increase in speed commences when the mold attains level position, and near the end of the charging operation.

10 In the other instance the relation is the same and the change in speed occurs with the parts in the same relation, that is with the mold level, and near the end of the charging operation. In both instances the speed changing means includes as the impelling force thereof a gravity operated plunger, that is a plunger biased toward downward movement by gravity, and hydraulic means to elevate the plunger. In the first example 15 the mold and its support serve the same purpose as the weight in the second example.

It will be evident from the description that the invention broadly considered is an assemblage of instrumentalities operating in 25 cycles, for charging a mold, and for rotating the mold through a sequence of selected speeds bearing a certain relationship to the charging operation, together with a single controlling means for initiating the cycles.

30 What is claimed as new is:

1. In centrifugal casting, a tilting mold normally biased to level position by gravity, elevating means to tilt the mold, a motor to rotate the mold, and means operated by 35 the movement of the mold toward level position to first increase and afterwards reduce the speed of the motor.

2. In centrifugal casting, a tilting mold normally biased to level position by gravity, 40 elevating means to tilt the mold, a motor to rotate the mold, means operated by the movement of the mold toward level position to first increase and afterwards reduce the speed of the motor, and means to charge 45 the mold operated by the movement thereof toward level position.

3. In centrifugal casting, a tilting mold normally biased to level position by gravity, elevating means to tilt the mold, a motor 50 to rotate the mold, a manual control for the motor, and means independent of the manual control operated by the movement of the mold toward level position to first increase and afterwards reduce the motor speed.

55 4. In centrifugal casting, a tilting mold normally biased to level position by gravity, elevating means to tilt the mold, a motor to rotate the mold, means operated by the movement of the mold toward level position to first increase and to afterwards reduce the speed of the motor, and means in 60 connection with said last named means enabling selection of the moment when the increase in speed commences.

65 5. In centrifugal casting, a tilting mold

normally biased to level position by gravity, elevating means to tilt the mold, a motor to rotate the mold, means operated by the movement of the mold toward level position to control the speed of the motor, the 70 elevating means including hydraulic mechanism, and means in connection therewith, to vary the speed of movement of the mold to level position.

6. In centrifugal casting, a tilting mold 75 normally biased to level position by gravity, elevating means to tilt the mold, a motor to rotate the mold, means operated by the movement of the mold toward level position to control the speed of the motor, the 80 elevating means including hydraulic mechanism, means in connection therewith to vary the speed of movement of the mold to level position, and means to vary the duration of the change from low to high speed. 85

7. In centrifugal casting, a tilting mold normally biased to level position by gravity, elevating means to tilt the mold, a motor to rotate the mold, a manual control for the motor, means operated by the movement 90 of the mold toward level position to vary the speed of the motor through a selected sequence of increase, decrease and stop, said means independent of the manual control.

8. In centrifugal casting, a tilting mold 95 normally biased to level position by gravity, elevating means to tilt the mold, a motor to rotate the mold, means to vary the speed of the motor in a selected sequence of increase, decrease and stop, and means whereby the 100 movement of the mold toward level position will initiate the operation of said means.

9. In centrifugal casting, a tilting mold normally biased to level position by gravity, elevating means to tilt the mold, a motor to rotate the mold, means to vary the speed of the motor in a selected sequence of increase, decrease and stop, means whereby the 105 movement of the mold toward level position will initiate the operation of said means, and means in connection with the speed varying means enabling selection of the moment when the increase in speed commences.

10. In centrifugal casting, a tilting mold 110 normally biased to level position by gravity, elevating means to tilt the mold, a motor to rotate the mold, means to vary the speed of the motor in a selected sequence of increase, decrease and stop, means whereby the 115 movement of the mold toward level position will initiate the operation of said means, and means in connection with the speed varying means enabling selection of the moment when the increase in speed commences, and the duration of the change from the initial 120 low to high speed.

11. In centrifugal casting, a tilting mold normally biased to level position by gravity, elevating means to tilt the mold, a motor to 125

- rotate the mold, a rotatable controller for the motor, means to operate the controller to vary the speed of the motor through a selected sequence of increase, decrease and stop, and means whereby the movement of the mold toward level position will initiate the operation of said means, said means including a gravity operated accelerating device in connection with the controller.
12. In centrifugal casting, a tilting mold normally biased to level position by gravity, elevating means to tilt the mold, a motor to rotate the mold, a rotatable controller for the motor, means to operate the controller to vary the speed of the motor through a selected sequence of increase, decrease and stop, means whereby the movement of the mold toward level position will initiate the operation of said means, said means including a gravity operated accelerating device in connection with the controller, and means in connection with the speed varying means enabling selection of the moment when the increase in speed commences.
13. In centrifugal casting, a tilting mold normally biased to level position by gravity, elevating means to tilt the mold, a motor to rotate the mold, a rotatable controller for the motor, means to operate the controller to vary the speed of the motor through a selected sequence of increase, decrease and stop, means whereby the movement of the mold toward level position will initiate the operation of said means, said means including a gravity operated accelerating device in connection with the controller, and means in connection with the speed varying means enabling selection of the moment when the increase in speed commences, and the duration of the change from the initial low to high speed.
14. In centrifugal casting, a tilting mold normally biased to level position by gravity, elevating means to tilt the mold, a motor to rotate the mold, a rotatable controller for the motor, means to operate the controller to vary the speed of the motor through a selected sequence of increase, decrease and stop, means whereby the movement of the mold toward level position will initiate the operation of said means, said means including a gravity operated accelerating device in connection with the controller and means in connection with the speed varying means enabling selection of the moment when the increase in speed commences, the elevating means including a hydraulic mechanism having an exhaust adjustable in capacity to enable regulation of the speed of descent of the mold.
15. In centrifugal casting, a tilting mold normally biased to level position by gravity, elevating means to tilt the mold, and means controlled to operate by the movement of the mold toward level position to rotate the mold through a sequence of selected speeds and to finally stop the motor.
16. In centrifugal casting, a rotatable mold, means to charge the mold including a tilting ladle delivering to the mold, and means synchronized with the tilting of the ladle to rotate the mold through a sequence of selected speeds to a final stop, said means controlled by the charging means to operate near the end of the charging operation.
17. In centrifugal casting, a rotatable mold, means to charge the mold including a tilting ladle delivering to the mold, and means synchronized with the tilting of the ladle to rotate the mold through a sequence of selected speeds to a final stop, said means controlled by the charging means to operate near the end of the charging operation, the mold pivoted near one end, elevating mechanism at the other end to incline the mold prior to the charging operation, and means operated by the return of the mold to level position to tilt the ladle.
18. In centrifugal casting, a tilting mold, a motor to rotate the mold, a controller for the motor, normally inoperative gravity operated mechanism to move the controller in a direction to speed up the motor, means operated by the mold near the end of its leveling movement to move said means into operative position, and other mechanism controlled by the descent of the mold to slow the motor after a selected period and to afterwards stop the motor.
19. In centrifugal casting, a rotatable mold, a motor for rotating the mold, a gravity operated accelerating device to speed up the motor, mechanism to charge the mold, and means operated by the charging mechanism to start the accelerating device.
20. In centrifugal casting, a rotatable mold, a motor for rotating the mold, a gravity operated accelerating device to speed up the motor, mechanism to charge the mold, means operated by the charging mechanism to start the accelerating device, and other means operated thereby to reduce the speed of the motor and to finally stop the same.
21. In centrifugal casting, a rotatable tilting mold, a motor for rotating the mold, means to tilt the mold, the mold being gravity operated to level position, a gravity operated accelerating device to speed up the motor, means operated by the mold near the end of its movement toward level position to start the accelerating device, and other means operated by said movement of the mold to reduce the speed of the motor and to finally stop the same.
22. In centrifugal casting, a rotatable tilting mold, a motor for rotating the mold, means to tilt the mold, the mold being leveled by gravity, a gravity operated accelerating device to speed up the motor, a ladle for charging the mold, a connection between the

- 5 mold and the ladle to empty said ladle while the mold is returning to level position, means operated by the mold near the end of its leveling movement to start the accelerating device, and other means operated by the mold in said movement to reduce the speed of the motor and finally stop the same.
- 10 23. In centrifugal casting, a rotatable mold, an electrically controlled motor for rotating the mold, a rotatable controller for the motor, a gravity operated accelerating device for the controller to speed up the motor, charging mechanism for the mold, means operated by the charging mechanism to initiate the operation of the controller accelerating device, and other means operated thereby for opening the motor circuit at a selected moment.
- 15 24. In centrifugal casting, a rotatable mold, a motor for rotating the mold, mechanism controlling the motor through a regular sequence of selected speeds to a final stoppage thereof, charging mechanism for the mold operating in synchronism with the motor speed controlling means, and means whereby the charging mechanism will initiate the operation of the speed controlling means near the end of the charging operation.
- 20 25. In centrifugal casting, a rotatable mold, a motor for rotating the mold, mechanism controlling the motor through a regular sequence of selected speeds to a final stoppage thereof, charging mechanism for the mold operating in synchronism with the motor speed controlling means, and means whereby the charging mechanism will initiate the operation of the speed controlling means near the end of the charging operation.
- 25 26. In centrifugal casting, a rotatable mold, a motor to rotate the mold, mechanism controlling the motor to cause the same to rotate the mold through a sequence of changes in speed to a final stop, said mechanism operating automatically when started and independently of the motor and the mold, and a single means to start the operation.
- 30 27. In centrifugal casting, a rotatable tiltable mold, instrumentalities operating to charge, level and rotate the mold, mechanism coordinating said instrumentalities and constraining them to operate in a selected cycle, and a single means for initiating a cycle.
- 35 28. In centrifugal casting, a rotatable tiltable mold, instrumentalities operating to charge, level and rotate the mold through a selected sequence of speeds to a final stop, mechanism coordinating said instrumentalities and constraining them to operate in a selected cycle, and a single means to initiate the cycle.

Signed at Birmingham, in the county of Jefferson and State of Alabama this 19th day of July, A. D. 1926.
